(57) **CLAIM**

We claim the ornamental design for a vehicle bumper, as shown and described.

DESCRIPTION

FIG. 1 is a perspective view of a vehicle bumper.

FIG. 2 is a left side elevation view of the vehicle bumper of FIG. 1.

FIG. 3 is a right side elevation view of the vehicle bumper of FIG. 1.

FIG. 4 is a front elevation view of the vehicle bumper of FIG. 1.

FIG. 5 is a rear elevation view of the vehicle bumper of FIG. 1.

FIG. 6 is a top plan view of the vehicle bumper of FIG. 1; and,

FIG. 7 is a bottom plan view of the vehicle bumper of FIG. 1.

The broken lines showing vehicle bumper features are provided for the purposes of illustrating environmental structures that form no part of the claimed design.

1 Claim, 3 Drawing Sheets
